PORTRABLE LAMP

Jacob A. Mehr, Kirkwood, Mo., assignor to Dazor Manufacturing Corp., St. Louis, Mo., a corporation of Delaware

Filed June 7, 1965, Ser. No. 85,582

Term of patent 14 years

(Cl. D48—20)

FIG. 1.

FIG. 2.

FIG. 3.

FIG. 4.

FIG. 5.

FIG. 6.

FIG. 1 is a side elevational view of a portable lamp embodying my new design;

FIG. 2 is a front elevational view thereof;

FIG. 3 is a top plan view thereof;

FIG. 4 is a rear elevational view thereof;

FIG. 5 is a plan view thereof with lamp head in extended position, and

FIG. 6 is an enlarged sectional view taken at line 6—6 of FIG. 5.

I claim:

The ornamental design for a portable lamp, substantially as shown and described.
